UNITED STATES PATENT OFFICE.

ANDREW LEONOFF, OF ELM PARK, NEW YORK.

DESIGN FOR A MONUMENT.

44,481.

Specification for Design.

Patented Aug. 12, 1913.

Application filed May 28, 1913. Serial No. 770,519. Term of patent 3½ years.

To all whom it may concern:

Be it known that I, ANDREW LEONOFF, a citizen of Russia, residing at Elm Park, in the county of Richmond and State of New York, have invented a new, original, and ornamental Design for Monuments, of which the following is a specification, reference being had to the accompanying drawing, forming a part thereof.

Referring to the drawing, there is shown a perspective view of a monument showing this design.

I claim—

The ornamental design for a monument as shown.

ANDREW LEONOFF.

Witnesses:

GEORGE L. THOM,
HELEN VAN ETEN.
